THOMAS H. THOMAS, OF EDGEWOOD, PENNSYLVANIA, ASSIGNOR TO THE WESTINGHOUSE AIR BRAKE COMPANY, OF WILMERDING, PENNSYLVANIA, A CORPORATION OF PENNSYLVANIA

ELECTROPNEUMATIC BRAKE

Application filed July 7, 1928. Serial No. 290,917.

This invention relates to railway traffic controlling apparatus and more particularly to the type controlled by energy received from the trackway.

5 The principal object of my invention is to provide an improved train stop apparatus of the above type.

Other objects and advantages will appear in the following more detailed description of 10 my invention.

In the accompanying drawings; Fig. 1 is a diagrammatic view of the pneumatic apparatus embodying my invention; Fig. 2 is a 15 diagrammatic view of a portion of the electric apparatus adapted to control the operation of the pneumatic apparatus shown in Fig. 1; and Fig. 3 is a development view of the brake valve device shown in Fig. 1.

As shown in Fig. 1 of the drawings, the 20 pneumatic apparatus may comprise a brake valve device 1, a cut-off valve device 2, a reduction limiting valve device 3 and a magnet valve device.

The brake valve device 1 comprises a casing 25 having a chamber 5 containing a rotary valve 4 adapted to be operated by a handle 6, and also contained in the casing is the usual equalizing discharge valve mechanism comprising a piston 7 and a discharge valve 8 adapted to be operated by said piston. The piston 7 has at one side a chamber 9, which is connected through a passage 10 and a choke plug 11 to an equalizing reservoir 12 and at the opposite side a chamber 13 which is connected through passage 14 to the brake pipe 15.

The cut-off valve device 2 comprises a casing having a longitudinal bore closed at the opposite ends by cap nuts 16 and 17, and containing an apertured partition wall 18 having screw-threaded engagement in the wall of said bore. The partition wall 18 forms at one side a chamber 19 containing a poppet valve 20, which is carried and operated by a stem 21, which extends through the aperture in partition wall 18 and is secured to a piston 22. Said piston forms a chamber 23 at one side and a chamber 24 at the opposite side, the latter chamber containing a spring 25 urging the piston inwardly and thereby tend-

ing to maintain the poppet valve 20 away from a seat ring 26, circumferentially formed about the aperture in partition wall 18.

The reduction limiting valve device 3 comprises a diaphragm 27 and a valve 28 adapted to be operated by said diaphragm. The diaphragm 27 has at one side a chamber 29 and at the opposite or lower side a chamber 30 connected to the atmosphere through an atmospheric passage 31. The valve 28 is contained in a chamber 32 which is connected through passage and pipe 33 to a reservoir 34 and has a fluted stem 35 extending upwardly through a bore in the partition wall 36 and into the chamber 30, wherein said stem engages the diaphragm 27. A spring 37 in chamber 32 urges the valve 28 upwardly towards its seat.

The magnet valve device comprises a magnet 38 connected to wires 40 and 41, and adapted to operate two double seat valves 43 and 44. The valve 43 is contained in a chamber 45 and has a fluted stem extending downwardly into a chamber 46, wherein said stem engages the upwardly extending fluted stem of valve 44, which is contained in a chamber 47. A spring 48 in chamber 47 engages valve 44, tending to seat said valve and unseat valve 43.

Upwardly projecting from and operable by the magnet 38 is stem 49 carrying at its outer end a switch 50 adapted upon energization of the magnet 38 to bridge the contact ends of wires 51 and 52. Energization of said magnet also seats valve 43 and unseats valve 44 at the same time that the switch 50 is moved downwardly. When the magnet is deenergized by cutting off the current flow through wires 40 and 41, the spring 48 seats valve 44, unseats valve 43 and shifts switch 50 upwardly, thereby disconnecting wires 51 and 52.

The current for operating the magnet 38 is supplied by a battery 53, and the circuit through said magnet is controlled by a cascade relay comprising two relay magnets 54 and 55, which are adapted to operate switches 56 and 57 respectively.

The magnet 54, as well as the magnet 55, is so designed as to be slow acting, that is, there

is a time delay between the opening of the circuit through said magnet and the operation of the switch 56 controlled by said magnet. The circuit through the magnet 54 is controlled by the switch 57 carried by magnet 55, while the circuit through said latter magnet is adapted to be controlled by a manually operated acknowledging switch comprising a handle 58 secured to and adapted to operate two switch contact fingers 59 and 60.

The circuit through magnet 55 is further controlled by an acknowledging relay comprising a magnet 61 and three contact fingers 62, 63 and 64 adapted to be operated by said magnet.

A decoding relay, which operates according to the track condition or signal indication, comprises a magnet 65 and two contact fingers 66 and 67, the contact finger 66 being connected by wire 40 to the positive terminal of the electric battery 53, while the contact finger 67 is connected by wire 73 to the negative terminal of said battery.

A signal 69, preferably in the form of a light, is located in the operator's cab of a locomotive, and is so connected by wires 70 and 71 to the acknowledging relay and decoding relay that normally, as when the track conditions are favorable, said light will be lit, but upon a change in track conditions, as from favorable to unfavorable, said light will go out.

In operation, when the track conditions are favorable, the decoding relay magnet 65 is energized and therefore holds the contact fingers 66 and 67 in the position shown in the drawings, while the circuit through the acknowledging relay magnet 61 is open, since the contact finger 67 of the decoding relay is in a position in which wire 72 from the acknowledging relay magnet 61 is disconnected from wire 73 leading to the negative terminal of battery 53.

With the decoding relay magnet 65 energized, the acknowledging relay magnet 61 de-energized and the acknowledging switch fingers 59 and 60 in the normal position, as shown in the drawings, a circuit is closed through the cascade relay magnet 55 by way of wire 40 from the battery 53, switch finger 66 of the decoding relay, wire 71, switch finger 63 of the acknowledging relay, wire 74, acknowledging switch finger 60, wire 75, magnet 55, wire 76, acknowledging relay switch finger 64, wire 70, decoding relay switch finger 67 and wire 73 to the negative pole of battery 53. Energization of magnet 55 shifts switch 57 so as to connect wires 40 and 77, thereby closing a circuit through the cascade relay magnet 54 by way of wire 40 from the positive terminal of battery 53, switch 57, wire 77, magnet 54 and wire 73 connected to the negative pole of battery 53. The magnet 54 is thus energized and causes switch 56 to operate and connect wires 41 and

73, thereby closing a circuit through the application magnet 38, by way of wire 40, application magnet 38, wire 41, switch 56, wire 73 and the battery 53, thus energizing said application magnet.

With the apparatus in the clear track condition as above described, the cab signal light 69 is lighted, since the light wires 71 and 70 are connected to the opposite poles of battery 53 through the contact fingers 66 and 67 of the decoding relay and wires 40 and 73.

When the application magnet 38 is energized, the switch 50 connects the wires 51 and 52 and also seats valve 43 and unseats the valve 44.

Fluid under pressure is supplied from a main reservoir 79 through a pipe and passage 80 to the rotary valve chamber 5 of the brake valve device and from pipe 80 to a feed valve device 81, which reduces the pressure of the fluid from that carried in the main reservoir to that normally carried in the brake pipe. Fluid at this reduced pressure then flows through pipe and passage 82 to the seat of the rotary valve 4.

With favorable or clear track conditions and with the brake valve handle 6 in the usual running position, fluid at feed valve pressure is permitted to flow from passage 82 to the cut-off valve piston chamber 24 through cavity 83 in the rotary valve 4, passage and pipe 84, magnet valve chamber 47, past the unseated valve 44, through chamber 46 and passage and pipe 85 and then from the piston chamber 24 to the equalizing piston chamber 9 by way of passage and pipe 86, past the ball check valve 87 in the brake valve device and through passage and pipe 10 and from thence through the choke plug 11 to the equalizing reservoir 12.

At the same time that the equalizing piston chamber 9 is charged, fluid at feed valve pressure flows through cavity 83 in the rotary valve 4 of the brake valve device and passage and pipe 88 to the cut-off valve piston chamber 23. The fluid pressures therefore become equal on the opposite sides of the cut-off valve piston 22, and permit spring 25 to maintain the cut-off valve piston 22 and cut-off valve 20 in the position shown in the drawings, in which fluid at feed valve pressure is permitted to flow from piston chamber 23 to the brake pipe 15 through the aperture in the partition wall 18, and the cut-off valve chamber 19. The equalizing piston chamber 13 in the brake valve device being connected to the brake pipe 15 becomes charged to the brake pipe pressure, and since the pressures on the opposite sides of the equalizing piston are therefore substantially equal, said piston holds the discharge valve 8 seated, in the usual manner.

With the brake valve device in running position, fluid under pressure flows from the rotary valve chamber 5 through port 89 in

the rotary valve 4 and passage and pipe 90 to diaphragm chamber 29 of the reduction limiting valve device and therein acts on diaphragm 27, causing said diaphragm to deflect downwardly and unseat valve 28, which then normally connects the reduction limiting reservoir 34 to the atmosphere through pipe and passage 33, valve chamber 32, past the unseated valve 28, through dia-
phragm chamber 30 and the atmospheric passage 31.

If the track conditions become unfavorable, the decoding relay magnet 65 becomes deenergized, thereby permitting the contact fingers 66 and 67 to drop and connect the wires 52 and 72. This interrupts the circuit to the cab signal light 69 through wires 70 and 71, causing the signal light to go out, so as to reveal to the engineer the unfavorable track conditions.

Since the circuit through the cascade relay magnet 55 is normally closed in the same manner that the cab signal light circuit is closed, the change in signal indication causes said magnet to become deenergized. However, the energizing circuit through the cascade relay magnet 54 remains closed for a period of time, since in accordance with the design of magnet 55, there is a predetermined time lapse between the opening of the circuit through said magnet and obtaining sufficient deenergization thereof to permit the switch 57 to shift and disconnect the wires 40 and 77 and thus open the circuit through the magnet 54. Then after another lapse of time, sufficient to deenergize magnet 54, the switch 56 moves down and opens the circuit through the application magnet 38. The reason for the delay in deenergization of magnets 54 and 55 after the circuit through said magnets is opened, will be hereinafter described.

Deenergization of the application magnet 38 permits spring 48 to seat valve 44, unseat valve 43 and shift switch 50 upwardly, so as to disconnect the wires 51 and 52.

The seating of valve 44 cuts off the supply of fluid at feed valve pressure from passage 84 to passage 85 and thence to the cut-off valve piston chamber 24 and the equalizing reservoir 12, while unseating of valve 43 permits fluid under pressure to quickly flow from said cut-off valve piston chamber through passage and pipe 85, chamber 46 in the application magnet valve device, past the unseated valve 43 and thence through pipe 33 to the reduction limiting reservoir 34. Fluid at feed valve pressure in the cut-off valve piston chamber 23 then shifts the cut-off valve piston outwardly against the reduced pressure of the fluid in chamber 24 and the resistance of spring 25, thereby causing the cut-off valve 20 to seat against the seat ring 26 and prevent further flow of fluid at feed

valve pressure from chamber 23 to chamber 19 and thence to the brake pipe 15.

Since the equalizing piston chamber 9 and equalizing reservoir 12 are connected to the cut-off valve piston chamber 24 through pipe 10, choke plug 91 and passage and pipe 86, the pressure in chamber 9 reduces at a rate governed by the flow area of said choke plug, which is such as to permit the pressure in the cut-off valve piston chamber 24 to remain at a low degree, so as to prevent reopening of the cut-off valve 20.

The reduction in pressure in the equalizing piston chamber 9 permits the pressure of the fluid from the brake pipe in the equalizing piston chamber 13 to shift the equalizing piston 7 upwardly and open the brake pipe discharge valve 8, thereby permitting fluid under pressure to flow from the brake pipe 15 to the atmosphere and thus cause a brake pipe reduction and consequent application of the brakes in the usual well known manner.

As shown in the drawings, with the brake valve handle 6 in running position, the reduction limiting valve 28 is normally maintained unseated by the fluid under pressure acting on diaphragm 27 in chamber 29. Under such a condition the reduction limiting reservoir 34 is connected to the atmosphere as hereinbefore described, so that when an automatic application of the brakes occurs, the fluid under pressure is completely vented from the equalizing reservoir 12 to the atmosphere and consequently permits a total venting of fluid under pressure from the brake pipe 15.

If it is desired to prevent a total venting of fluid under pressure from the brake pipe as just described, then upon initiation of the brake application, the brake valve handle 6 is moved to lap position, in which the reduction limiting valve diaphragm chamber 29 is vented to the atmosphere through pipe and passage 90 and the atmospheric passage 92 by way of a cavity (not shown) in the rotary valve 4 which, in lap position of the handle 6, is adapted to connect the passages 90 and 92.

Venting of the diaphragm chamber 29 permits spring 37 to seat the valve 28, so that when an automatic application of the brakes is effected, as hereinbefore described, the reduction in equalizing reservoir pressure is limited to equalization of pressures in the equalizing reservoir 12 and the reduction limiting reservoir 34, it being noted that the engagement of the valve 20 with its seat prevents piston 22 from moving to the left sufficiently to close the passage 85. Such a limited reduction in equalizing reservoir pressure permits a sufficient decrease in brake pipe pressure, effective in the equalizing piston chamber 13, to make a full service application of the brakes.

If, for any reason, it is desired to effect an

application of the brakes by operation of the brake valve device 1 in the usual manner, instead of permitting the application to be automatically effected as hereinbefore described, then, when the decoding relay magnet 65 becomes deenergized due to the change in traffic conditions, and the cab signal light 69 goes out, as hereinbefore described, the operator shifts the acknowledging switch contacts 59 and 60 downwardly by movement of the handle 58.

In the downward position of the acknowledging switch, the contact 60 disconnects wires 75 and 74 through which the circuit to the cascade magnet 55 was closed prior to deenergization of the decoding relay magnet 65. In this downward position, the other switch contact 59 connects wires 51 and 93, thereby closing a circuit through the acknowledging relay magnet 61 by way of wire 40 from the positive terminal of battery 53, switch arm 66 of the decoding relay, wire 52, the application magnet switch 50, wire 51, acknowledging switch arm 59, wire 93, acknowledging relay magnet 61, wire 72, decoding relay switch arm 67 and wire 73 leading to the negative pole of battery 53.

Closing a circuit through the acknowledging relay magnet 61 energizes same, which causes the switch arms 62, 63 and 64 to be pulled upwardly. The arm 62 then connects with wire 40 from the positive terminal of the battery 53, thus permitting current to flow from said battery through the relay magnet 61, wire 72, decoding relay switch arm 67 and wire 73 to the negative pole of battery 53, thereby closing a second circuit through the acknowledging relay magnet 61. The acknowledging switch arms 59 and 60 are then returned to the normal position as shown in the drawings, and the acknowledging relay magnet 61 remains energized.

When the acknowledging switch is returned to its normal position and with the acknowledging relay magnet 61 energized as just described, the circuit is again closed through the cascade relay magnet 55 by way of wire 40 from the positive terminal of the battery 53, acknowledging relay magnet switch arm 63, wire 74, acknowledging switch arm 60, wire 75, cascade relay magnet 55, wire 76, acknowledging relay magnet switch arm 64 and wire 73 from the negative pole of battery 53. Reclosing the circuit through magnet 55 closes the circuit through magnet 54 in case the latter circuit is opened. Magnet 54 then being energized maintains the application magnet 38 energized.

It should be noted that the circuit through the cascade relay magnet 55 is opened as soon as the decoding relay magnet 65 is deenergized, but that the application magnet 38 is not deenergized until a predetermined time after the deenergization of said decoding relay magnet 65 by a change

in signal indication in the manner hereinbefore described. It is during this time period that the engineer must acknowledge the change in signal indication, if he wishes to initiate the brake application instead of permitting the application to be automatically made in the manner hereinbefore described.

In acknowledging a change in signal indication, the circuit closed in energizing the acknowledging relay magnet 61 is controlled through the application magnet switch 50, so that in case the engineer fails to acknowledge before deenergization of the magnet 38 and the consequent upward movement of switch 50, then the brake application is caused automatically in the manner hereinbefore described and is thus out of the control of the engineer.

Assuming that the change in signal indication is properly acknowledged by the engineer before deenergization of the application magnet 38, then in order to manually effect an application of the brakes, the brake valve handle is operated to turn the rotary valve 4 to service position, in which the equalizing piston chamber 9 and equalizing reservoir 12 are connected to the atmosphere through passage 10, choke plug 91, passage 86, a cavity (not shown) in the rotary valve 4 and the atmospheric passage 92. The flow area of choke plug 91 is less than that of choke plug 11, so that the pressure in said equalizing piston chamber and reservoir remains substantially equal during a reduction in pressure therein.

Reducing the pressure in the equalizing piston chamber 9 permits the higher brake pipe pressure in the equalizing piston chamber 13 to shift the equalizing piston 7 upwardly and unseat the brake pipe discharge valve 8, which then permits fluid under pressure to flow from the brake pipe 15 to the atmosphere by way of passage 14, chamber 13 and pipe and passage 95.

When the brake pipe pressure is reduced a degree equal to the degree of reduction in equalizing reservoir pressure, the equalizing piston 7 operates to close the discharge valve 8 in the usual well known manner.

In order to release an application of the brakes caused by operation of the brake valve device, the brake valve handle 6 is turned to running position in which the brake pipe 15, and the equalizing reservoir 12 are recharged in the same manner as hereinbefore described.

In case a brake application is automatically effected due to unfavorable track conditions, such an application can not be released until the track conditions become favorable again, which then causes the decoding relay magnet 65 to become reenergized so as to effect the return of the switch arms 66 and 67 to their normal position as shown in the drawings,

in which position, wires 72 and 73 are disconnected, thereby opening the circuit through the acknowledging relay magnet 61. Said magnet is thereby deenergized, which 5 permits the switch arms 62, 63 and 64 to drop to their normal position. With the decoding and acknowledging relay magnets 65 and 61, respectively, returned to their normal positions and the brake valve handle 6 in 10 running position as shown in the drawings, the brakes are released by recharging the brake pipe 15 in the same manner as hereinbefore described.

A double heading cock 96 is interposed in 15 the pipes 88 and 95 in such a manner that the flow of fluid under pressure through said pipes may be controlled through a plug valve 97, which may be turned by a handle 98 to either the position shown in the drawings, 20 in which communication is permitted through pipe 88 and from pipe 95 to the atmosphere, or to a second position in which such communication is cut off. This is desirable under certain conditions, as will be now 25 explained.

In the case of double heading, the brake controlling apparatus on the second locomotive is cut out by means not shown and the application magnet 38 is therefore deenergized. The double heading cock 96 is turned, so as to close communication through pipe 88 and from pipe 95 to the atmosphere on said second locomotive, so that with the equalizing piston chamber 9 vented to the atmosphere 30 by way of the unseated magnet valve 43, and the discharge valve 8 unseated by the brake pipe pressure in the equalizing piston chamber 13, fluid under pressure can not flow from the brake pipe 15 to the atmosphere and 40 thus interfere with the control of brake pipe pressure on the leading locomotive.

If only the brake pipe discharge passage 95 were controlled through the double heading cock 96, as just described, then the engineer could prevent an automatic application of the brakes from occurring by merely operating a locomotive with said cock in the closed position and then turning said cock to the open position only when he desired that 50 an application should be made. In order to prevent such undesired operation, the supply of fluid under pressure to the brake pipe, by way of passage and pipe 88, is also controlled through said cock, so that in order to charge 55 the brake pipe 15 and maintain the pressure therein so as to prevent brake pipe leakage from applying the brakes, the double heading cock has to be in the open position, as shown in the drawings, in which the brake pipe discharge passage 95 is also open.

It will be noted that the time from the change in signal indication to the deenergization of the application magnet 38, during 65 which the engineer may acknowledge in order to effect a brake application manually, is

equal to the sum of the lag or delay in deenergization of the cascade relay magnets 55 and 54 from the time the circuits through said magnets is opened. For instance, there may be a two second delay from the time the 70 circuit through magnet 55 is opened until the downward movement of the switch. With a like delay in magnet 54 there would be a 4 second time interval between the change in signal indication and opening of the circuit 75 through the application magnet 38. Thus according to the time interval desired, the number of magnets used, similar to 54 and 55, may be varied, or the design of said magnets may be changed in order to effect the delay desired. 80

The choke plug 11 is provided in passage 10, leading to the equalizing reservoir 12, so that in charging, the fluid under pressure flowing past the ball check valve 87 into the 85 equalizing piston chamber 9 will quickly build up a pressure therein ahead of the build-up of pressure in the equalizing reservoir 12, so as to prevent the brake pipe pressure build-up in equalizing piston chamber 90 13 from raising the equalizing piston 7 and thereby unseating the discharge valve 8 and permitting fluid under pressure to flow from the brake pipe to the atmosphere.

From the foregoing description of operation, it will be noted that when the traffic conditions change from favorable to unfavorable, the decoding relay magnet 65 is deenergized and opens a circuit through the slow acting relay magnet 55. Upon deenergization of relay magnet 55, a circuit through the slow acting relay magnet 54 is opened, which in turn operates to open a circuit through the application magnet 38. Upon deenergization of the application magnet 38, the cut-off valve device 2 operates 100 to cut off the supply of fluid under pressure to the brake pipe 15 and the equalizing piston 7 and brake pipe discharge valve 8 105 operate to effect a reduction in brake pipe 110 pressure and cause an application of the brakes to be effected.

The equalizing piston 7 operates upon a reduction in equalizing reservoir pressure in piston chamber 9, the pressure in the equalizing reservoir 12 reducing by flow to the reduction limiting reservoir 34. With the reduction limiting reservoir open to the atmosphere through the reduction limiting valve device 3, as when the brake valve device is in running position, a complete venting of fluid from the equalizing reservoir and consequently from the brake pipe results. 115

In order to limit the brake pipe reduction to only that required to effect a full service application of the brakes, the engineer can turn the brake valve device from running position to lap position. By so doing, the reduction limiting valve device 3 operates to close the atmospheric connection to 120 130

the reduction limiting reservoir. As a result, the reduction in equalizing reservoir pressure is limited to equalization in the reduction limiting reservoir, and a brake pipe reduction of corresponding degree is effected in the usual well known manner. After a train control application of the brakes is effected in the manner just described, the brakes can not be released until after the traffic conditions become favorable and the decoding magnet 65 is again energized.

In order to avoid the possible delay in schedule caused by a train control application of the brakes, the engineer may prevent 15 a train control application of brakes and apply the brakes in the usual manner by the brake valve device and then proceed with caution.

In order to apply the brakes by operation 20 of the brake valve device 1 instead of permitting the train control apparatus to apply the brakes, the engineer shifts the acknowledging switch contacts 59 and 60 to their lower position after the decoding relay magnet 65 becomes deenergized. In the lower position of the acknowledging switch contacts, a stick circuit is closed through the acknowledging relay magnet 61, after which the acknowledging switch contacts are returned to their normal position for reclosing 25 the circuit through the cascade relay magnet 55, the energization of magnet 55 thereby preventing the deenergization of the application magnet 38. It will however be noted that the stick circuit through the acknowledging relay magnet 61 is controlled by the application magnet switch 50, so that if the application magnet is deenergized at the time the acknowledging switch contacts 30 59 and 60 are moved to their lower position, the train control application of brakes can not be stopped. There is, however, a delay period between the deenergization of the decoding relay magnet 65 and the deenergization 35 of the application magnet 38, which is measured by the additive slow action of the cascade relay magnets 55 and 54, and it is during this period that the engineer must acknowledge to close the stick circuit above 40 mentioned.

When the engineer properly acknowledges the change in traffic conditions, he moves the brake valve device to service position, in which a service application of the brakes is 45 effected in the usual manner.

In addition to the above, a choke plug 11 is provided to restrict the charging of the equalizing reservoir 12 so as to hasten the build up of pressure in chamber 9 on the equalizing piston 7 in order to prevent the build up of brake pipe pressure in chamber 13 from shifting the equalizing piston 7 to open the brake pipe discharge valve 8 and cause undesired venting of fluid under pressure from the brake pipe. A choke plug 91

is provided to restrict the flow of fluid under pressure from the equalizing reservoir to chamber 24 of the cut-off valve device 2 when a train control application of the brakes is effected, so as to prevent a sufficient 70 pressure to be obtained in said chamber to cause an undesired opening of the cut-off valve 20.

While one illustrative embodiment of the invention has been described in detail, it is 75 not my intention to limit its scope to that embodiment or otherwise than by the terms of the appended claims.

Having now described my invention, what I claim as new and desire to secure by Letters Patent, is:—

1. In an electro-pneumatic brake, the combination with a brake pipe and a magnet valve device, of a cut-off valve device controlled by said magnet valve device and operative upon energization of the magnet of said magnet valve device to supply fluid under pressure to said brake pipe and operative upon deenergization of said magnet to cut off the supply of fluid under pressure to said brake pipe, and an equalizing valve mechanism operative upon deenergization of said magnet to vent fluid under pressure from said brake pipe.

2. In an electro-pneumatic brake, the combination with a brake pipe and a magnet valve device, of a valve for controlling the supply of fluid under pressure to said brake pipe, a piston for operating said valve, said piston being controlled by said magnet valve device, another valve for venting fluid under pressure from said brake pipe, and a piston controlled by said magnet valve device for operating the last mentioned valve.

3. In an electro-pneumatic brake, the combination with a brake pipe, of a discharge valve for venting fluid under pressure from said brake pipe, an equalizing piston for operating said discharge valve, a cut-off valve for supplying fluid under pressure to said brake pipe, a piston for operating said cut-off valve and subject on one side to fluid under pressure, a magnet, a valve operative upon energization of said magnet to supply fluid under pressure to one side of said equalizing piston for closing said discharge valve and to supply fluid under pressure to the other side of said cut-off valve piston, a spring for opening said cut-off valve to supply fluid under pressure to said brake pipe when the opposite sides of the cut-off valve piston are subject to fluid under pressure, and another valve operative upon deenergization of said magnet to vent fluid under pressure from the one side of said equalizing piston for opening said discharge valve to vent fluid under pressure from said brake pipe, said other valve being also operative upon deenergization of said magnet to vent fluid under 120

pressure from one side of the cut-off valve piston for closing said cut-off valve.

4. In an electro-pneumatic brake, the combination with a brake pipe, of a discharge valve for venting fluid under pressure from said brake pipe, an equalizing piston for operating said discharge valve, an equalizing reservoir connected to a chamber at one side of said equalizing piston, a magnet, a valve operative upon energization of said magnet to supply fluid under pressure to said equalizing reservoir and to said chamber for operating the equalizing piston to close said discharge valve, means for restricting the supply of fluid under pressure to said equalizing reservoir, another valve operative upon deenergization of said magnet for venting fluid under pressure from said chamber and equalizing reservoir, and means for restricting the venting of fluid under pressure therefrom.

5. In an electro-pneumatic brake, the combination with a brake pipe, of a discharge valve for venting fluid under pressure from said brake pipe, an equalizing piston for operating said discharge valve, an equalizing reservoir connected to a chamber at one side of said equalizing piston, a magnet, a valve operative upon energization of said magnet to supply fluid under pressure to said equalizing reservoir through a restricted passage and to said chamber through an unrestricted passage, and another valve operative upon deenergization of said magnet for venting fluid under pressure from said chamber and equalizing reservoir through another restricted passage.

6. In an electro-pneumatic brake, the combination with a brake pipe and a brake valve device, of a magnet valve device for effecting a reduction in brake pipe pressure, and means associated with said magnet valve device operative in accordance with the position of said brake valve device for controlling the degree of reduction in brake pipe pressure.

7. In an electro-pneumatic brake, the combination with a brake pipe and a brake valve device, of a magnet valve device for effecting a reduction in brake pipe pressure, and means associated with said magnet valve device operative to completely vent the fluid under pressure from the brake pipe when said brake valve device is in one position, and to limit the degree of brake pipe reduction when said brake valve device is in another position.

8. In an electro-pneumatic brake, the combination with a brake pipe, a reduction limiting reservoir and a brake valve device, of a magnet valve device for venting fluid under pressure from said brake pipe to said reservoir, and a valve controlled by said brake valve device for controlling communication from said reservoir to the atmosphere.

9. In an electro-pneumatic brake, the com-

bination with a brake pipe and a brake valve device, of an equalizing valve mechanism for venting fluid under pressure from said brake pipe, an equalizing reservoir normally charged with fluid under pressure for governing the operation of said equalizing valve mechanism, a magnet, a valve operative upon energization of said magnet for supplying fluid under pressure to said equalizing reservoir and upon deenergization of said magnet to cut off the supply of fluid under pressure to said reservoir, a reduction limiting reservoir, another valve operative upon energization of said magnet for closing a connection from said equalizing reservoir to said reduction limiting reservoir and upon deenergization of said magnet to vent fluid under pressure from said equalizing reservoir to said reduction limiting reservoir, and pressure sensitive means normally establishing a communication through which said reduction limiting reservoir is vented and having a position for closing said communication, said brake valve device being operative to control the operation of said pressure sensitive means.

10. In an electro-pneumatic brake, the combination with a brake pipe and a brake valve device, of an equalizing valve mechanism for venting fluid under pressure from said brake pipe, an equalizing reservoir normally charged with fluid under pressure for governing the operation of said equalizing valve mechanism, a magnet, a reduction limiting reservoir, valve means operated upon energization of said magnet to supply fluid under pressure to said equalizing reservoir and upon deenergization of said magnet to vent fluid under pressure from said equalizing reservoir to said reduction limiting reservoir, and valve means operative in accordance with the position of said brake valve device for controlling an atmospheric communication from said reduction limiting reservoir to the atmosphere.

11. In an electro-pneumatic brake, the combination with a brake pipe, of valve means for controlling the supply of fluid under pressure to and the venting of fluid under pressure from said brake pipe, electro-responsive means for controlling said valve means, and a valve device for controlling the communication through which fluid under pressure is supplied to the brake pipe and the communication through which fluid under pressure is vented from the brake pipe, said valve device being operative to close said communications.

12. In an electro-pneumatic brake, the combination with a brake pipe, of a valve device for controlling the supply of fluid under pressure to said brake pipe and operated by a variation in fluid pressure to cut off the supply of fluid under pressure to said brake pipe, a valve device operated by a variation in fluid pressure to vent fluid under pressure

from the brake pipe, and electro-responsive means for varying the fluid pressure on said valve devices.

13. In an electro-pneumatic brake, the combination with a brake pipe, of a cut-off valve for controlling the supply of fluid under pressure to the brake pipe, electro-responsive means for operating said cut-off valve device to cut off the flow of fluid under pressure to said brake pipe, an equalizing valve mechanism for venting fluid under pressure from the brake pipe, and a manually operated valve for controlling the communication through which fluid is vented from the brake pipe and the communication through which fluid under pressure is supplied to the brake pipe.

14. In an electro-pneumatic brake, the combination with a brake pipe, of electro-responsive means for controlling the supply of fluid under pressure to and the venting of fluid under pressure from the brake pipe, and a manually operated valve having a position for closing the communication through which fluid under pressure is supplied to said brake pipe and the communication through which fluid under pressure is vented from the brake pipe by operation of said electro-responsive means.

15. In testimony whereof I have hereunto set my hand, this 2nd day of July, 1928.

THOMAS H. THOMAS.
